TELEGRAPHIC RECORDER

Filed March 23, 1927

UNITED STATES PATENT OFFICE

ERNEST A. FALLER, OF BROOKLYN, NEW YORK

TELEGRAPHIC RECORDER

Application filed March 23, 1927. Serial No. 177,850.

The present invention relates to improved recording mechanisms for signals, and more particularly the invention relates to mechanisms for making a permanent record of signals or messages transmitted electrically or otherwise from a distant point.

Various forms of recorders for automatically recording telegraphic signals or messages on a moving tape by perforating, slashing or embossing the tape, and by marking the tape through the action of chemicals, inks, pyrographic effects and the like, all of which have proven more or less unsatisfactory in operation where accuracy and reliability are essential, as for example, in fire alarm and way station telegraph signalling operations. The most common forms of such recorders are the ink and the perforating or slashing recorders. The ink recorders in common use utilize felt inking rollers for the marker, which require frequent attention to maintain the roller properly inked and are subject to smearing of the record incidental to too much ink, drying of the ink on the filled roller in operation with consequent loss of signals, and to other practical disadvantages. As a result of defects of the ink registers of the prior art, perforating and slashing registers of various types have been devised in which perforations are made in a paper tape. While avoiding the troubles incident to inking, the perforating recorders are subject to other disadvantages among them being the fact that the tape cannot be driven continuously as in the inking recorders and the clock driving mechanism must be frequently rewound because of the amount of energy necessary to operate the punchers for perforating the tape. A further disadvantage of the perforating registers or recorders is that they are not readily adapted for recording dot and dash telegraphic codes, such for example, as the Morse or Continental telegraphic codes.

To avoid the disadvantages incident to the

prior tape recorders various efforts to develop recorders provided with ink ribbons such as are used in typewriter mechanisms have been made, but have been unsuccessful. I have found that the ordinary typewriter ink ribbon mechanisms cannot be applied to telegraphic registers utilizing a continuously fed tape to record signals for the reason that in a typewriter mechanisms the ribbon is stationary during the printing operation. For successful operation of a ribbon inking device in telegraphic tape recorders, I have found that it is necessary to move the ink ribbon in the direction of movement of the recording tape during the printing operation in order that a legible record may be made. A further requirement of a practical ink ribbon tape recorder is that the same section of the ribbon must not be reused before the ink has had time to seep to the places left bare by the transfer of ink from the ribbon to the tape in the printing of the signals. In prior efforts to utilize ink ribbons in recorders of this type, ribbons of such length have been used that the same section of the ribbon is reused about every thirty seconds or less in the operation, and the ink in the used section of the ribbon is rapidly used to such an extent that failure to mark occurs shortly after such recorders are put into continuous service. I have, however, discovered that if a sufficient interval of time, usually from 15 to 30 minutes is allowed between each use of a given ribbon section, ink will seep from the surrounding ribbon parts to the ribbon section that is used in the marking, and continuous reliable marking operation may be maintained. I have found with a good hectographic ribbon it is essential that a ribbon length of at least six feet and preferably a length of about ten feet should be utilized for practical operation. I have found when a ribbon of this length is used with a telegraph register such as is used for Morse recorders

- and in fire alarm telegraphs, the ink will slowly seep toward the spot left bare by the printing of signals, and the printing of signals may be carried on without mutilation in continuous operation of the device. A primary object of my invention is to provide a ribbon inking recorder mechanism for telegraphic signals, adapted for continuous operation. 6
- Another object of the invention is to provide an ink ribbon recorder in which a sufficient length of ribbon is utilized to permit the ink to seep to the used sections of the tape before the reuse so that continuous 10 operation may be maintained. 10
- Still another object of the invention is to provide a novel ribbon inking recorder mechanism for recording signals in code form in which the ribbon is continuously 15 fed in the same direction as the recording tape. 20
- A further object of the invention is to provide a convenient, compact, portable ribbon inking mechanism suitable for use as a telegraphic code signals recorder, and adapted for continuous operation in which a discontinuous ink ribbon is automatically 25 reversed and fed at all times in the direction of movement of the tape upon which 30 the signals are recorded. 30
- Further objects of the invention will appear in the following description of the preferred embodiment thereof and are such as may be attained by a utilization of the various 35 combinations, sub-combinations, and principles hereinafter set forth, and as more fully defined by the terms of the appended claims. 40
- Referring to the drawings—
- Figure 1 is a side elevation of a preferred embodiment of my invention as applied to a typical recorder or register utilized for recording Morse, fire alarm, and similar signals. 45
- Figure 2 is a side elevation, partially in section, of the form of invention shown in Figure 1.
- Figure 3 is a plan view partially in section of the form of invention shown in Figure 1. 50
- Figure 4 is a fragmental view showing a modified arrangement of the feeding mechanism utilized in connection with the form of invention shown in Figure 1.
- As shown in the drawings, 1 indicates the casing of a typical tape recorder or register. Journaled in casing 1 is the usual winding shaft 2 of a spring driven clockwork for the propulsion of the recorder 55 mechanism. The clockwork or spring motor comprises a gear wheel 3 rotatably mounted on shaft 2 with which the drum 4 is integrally formed. Disposed within the drum or barrel 4 is a spiral main spring (not shown) of the usual type, which has its 60 inner end secured to shaft 2 and its outer end secured to the inner circumference of barrel 4. Rotatably mounted on shaft 2 is a bevel gear 5 forming part of my invention on which a pawl 6 is pivotally mounted. Pawl 6 is spring pressed into engagement with ratchet wheel 7 which is secured to and rotatable with winding shaft 2. 70
- The rotation of driving gear 5 is prevented by a usual type of self stopping device (not shown) controlled by the armature 8 of the receiving magnet 9, which is supported by suitable brackets from the casing 1 in the usual manner. As is well known in the art self starting and self stopping devices of this type are arranged so that as long as the magnet 9 becomes energized at intervals of not more than a predetermined length the gear 5 will remain in rotation and the gear 3 and clockwork will be stopped only when the magnet is not energized for the predetermined length of time. 75
- The armature 8 is secured to spindle 10 rotatably mounted on brackets secured to casing 1, and secured to spindle 10 is marking lever 11 which together with armature 8 is normally held in retracted position by the action of spring 12 secured to lever 11. 80
- Supported in the end of lever 11 is a marking stylus 13 which upon energization of magnet 9 is forced upward against the tape 14 to effect a marking of the tape 14. Tape 14 passes normally around a guiding roller 15 and in a straight line over stylus 13 to the tape feeding rollers 16 and 17. 85
- Roller 16 is preferably provided with a sharp finely toothed or serrated periphery to insure positive propulsion of the tape, and is driven by a shaft 18 which in turn 90 is driven through a gear train of any usual type from the gear 3 (not shown). Roller 17 is flat and is rotatably mounted on the upper end of supporting arm 19, the lower end of which is pivotally secured at 20 to the casing 1. A spring 22 interposed between arm 19 and casing 1 urges the roller 17 yielding downward forcing the tape into engagement with the periphery of feed wheel 16. The mechanisms not shown in detail form no part of my invention and are 95 of any usual tape register or recorder type. As will be understood by those skilled in the art, shaft 2 is adapted to be rotated by a key fitting over the square end thereof to 100 wind the main spring of the spring motor, and with the gear 3 held stationary by the stop mechanism, pawl 6 will engage a tooth of ratchet wheel 7 and will prevent unwinding of the spring. 105
- The essentially novel features of my invention reside in the ink ribbon mechanism hereinafter set forth. In locations where ample space is provided, a practical ink ribbon recorder may be made by providing 110 a continuous ink ribbon of from six to 115
- 120
- 125
- 130

- ten feet or more in length supported on suitable pulleys with a section continuously interposed between the tape upon which the record is to be made and a platen member above stylus 13 together with means for driving the ribbon continuously in the direction of feed of the recording tape, and this type of recorder is within the scope of my invention.
- 5 In most instances, sufficient space for recorders of this type is not available. In the portable form of my invention bevel gear 5 meshes with and drives a bevel pinion 23 which is secured to and drives a vertical shaft 24 supported in a bearing 25 of casing 1 and in a suitable bearing in the supporting bracket 26 secured to casing 1 by screws 27. Secured to and driven by shaft 24 is a gear 27 driving an idler gear 28 rotatably supported from the yoke 26. Gear 28 meshes with and drives a pinion 29 which is rigidly secured to and adapted to drive a frame structure 30. Frame 30 is rotatably supported on a vertical post 31, provided 20 with an enlarged head 32 at its lower end and against which the frame 30 rests, and secured at its upper end by means of the nut 33 to bracket 26. Rotatably secured to extension 34 of frame 30 by means of stud 35 is a roller 36 so positioned that the end of the stylus 13 will press the tape 14 against the ink ribbon 37 as it passes over roller 36 when the magnet 9 is energized. In the preferred embodiment of the invention stylus 30 35 13 is positioned to one side of the center of ribbon 37 for the purpose of using different sections of the ribbon when the ribbon mechanism is reversed as will more fully hereinafter appear.
- 40 Ribbon 37 is wound upon ribbon spools 38 and 39 which are removably held on the end of drive spindles 40 and 41, respectively by means of the knurled thumbscrews 42 threaded on the end of the spindles. When 45 positioned on the spindles 40 and 41 respectively, the spools are driven with the spindles by a driving pin 43 (Figure 3) secured to the spindles. Spindles 40 and 41 are journaled in suitable bearing sections 44 of frame 30 and secured thereto are the pinions 45 and 46. Pinions 45 and 46 mesh with gears 47 and 48 respectively which are provided with the tubular hub sections 49 and 50 mounted for rotation on 50 the stud 51 which in turn is secured in framework 30. Secured to gear 47 is a drum section 51 to the inner periphery of which the outer end of a long thin spiral spring member 52 is secured by screw 53.
- 55 The inner end of the spring 52 is secured to hub section 49 of gear 48 by means of screw 54. Pivotaly supported on ends of frame 30 by means of pins 55 and 56 are the stop members 57 and 58 between which 60 spring 59 (Figure 1) is secured. Members 57 and 58 extend downward between the flanges of the ribbon spools 38 and 39 and are guided in their swinging movement by pins 60 and 61 secured in the lower ends of frame 30 and extending through guide slots formed adjacent the lower end of stop members 57 and 58. The lower ends of stop members 57 and 58 extend beneath the lower edge of frame 30 and are adapted to engage the stop member 62 secured to 65 casing 1 to control the position of frame 30 as will more fully hereinafter appear.
- Operation.*
- With the parts as shown in Figure 2, 80 rotation of frame 30 about post 31 under influence of the main spring and bevel gear 5 is prevented by engagement of the lower end of the stop member 57 with frame bracket 62.
- Upon receipt of the first impulse of a series of signals by magnet 9, the self-starting mechanism will be actuated to free gear 3 for rotation under the influence of main spring, and will drive the tape feed wheel 90 16 in the direction of the arrow shown in Figure 1 to advance tape 14 continuously from left to right. As magnet 9 is energized, the moving tape will be forced upward by the stylus 13 into engagement with ink ribbon 37 and the ink ribbon will be forced against roller 36. It will be noted that spring 52 will apply substantially equal and opposite forces through gears 47 and 48, and pinions 45 and 46 to ribbon spools 38 and 39 so that the ribbon 37 will be held taut across roller 36, but there will be no normal tendency for the ribbon to move in either direction. When, however, stylus 13 forces tape 14 upward into engagement with the ribbon 37, the ink ribbon will move forward in the direction of movement of the tape winding up on the one spool and unwinding from the other. In this way a freshly inked surface of the ribbon will be in contact with the tape over the stylus so long as the magnet is energized, and a mark depending upon the length of the impulse received by the magnet 9 will be made on the tape. While fresh ink sections of the ribbon will be utilized for each marking it will be noted that the ink ribbon is only advanced when a marking signal is received. As the operation of the device continues, the ribbon will wind up on spool 38 and will unwind on spool 39 until the ribbon on spool 38 forces stop member 57 outward about its pivot 55 a sufficient distance to disengage the end thereof from stop member 62. When this occurs, frame 30 will be freed 110 for rotation about the post 31 under the influence of the main spring acting through bevel gear 5, pinion 23, shaft 24, gears 27 and 28, and a pinion 39. Frame 30 will now rotate through an angle of 180 degrees until 115 120 125 130

the bottom of the stop member 58 engages stop 62 positioning the ribbon spool 39 to the left and the ribbon spool 38 to the right in Figure 1. During this rotation of the frame 30, it will be noted that no loss of signals will occur during this interval. During the marking operations of the register, printing ribbon will again be moved with the tape to the left in Figure 1 and will 10 now be wound up on spool 39 and unwound from spool 38 until the ribbon forces the end of the stop member 58 out of engagement with the stop 62, permitting the parts again to rotate through an angle of 180 degrees.

If the stylus 13 is positioned slightly to one side of the center of the ribbon 37, when the frame 30 rotates through 180 degrees, the marking will occur at an equal 20 distance on opposite sides of the center of ribbon 37 and different sections of the ribbon will alternately be used giving more time for the ink to seep to the used sections of the ribbon, and more efficiently utilizing 25 the ribbon. By making the stylus 13 laterally adjustable on actuating lever 11, a maximum life and efficiency of utilization of the ribbon is secured.

It will be seen in the mechanism so far 30 described a novel compact ink ribbon mechanism for recording mechanisms utilizing an ink ribbon of sufficient length to permit continuous operation is provided in which movement of the ink ribbon occurs in the 35 direction of movement of the tape during all marking operations, while at the same time a discontinuous ribbon is utilized.

In the mechanism so far described, the pressure exerted by the stylus and the movement of the tape on which the messages are recorded are relied upon to shift the ink 40 ribbon. This requires a sufficiently heavy current in the magnet 9 to get the desired frictional contact between the tape and the 45 ink ribbon. It is frequently desirable to operate the receiving magnet with very light currents, as when the magnet is inserted directly in a long main line. To insure continuous driving of the tape under these 50 conditions, as shown in Figure 4, a special feeding mechanism may be provided consisting of a shaft 64 geared to and continuously driven from the tape driving shaft 18 in a manner that will be obvious 55 to one skilled in the art. Secured on one end of shaft 64 is an eccentric 65 on which is mounted an eccentric strap 66 actuating ribbon stepping pawl 67. Pawl 67 is held inclined by its weight towards a fixed 60 stop 68 supported from casing 1 in any suitable manner, and the upper end thereof is provided with a toothed end 69 adapted to engage the teeth 70 of the ribbon spools. Pawl 67 is provided with a flared 65 edge 71 adapted to be engaged by the flanges

of the ribbon spools 38 and 39 to cam the pawl slightly away from stop 68 during the rotation of frame 30 to reverse the winding of the ribbon. When this stepping device for the ribbon is utilized, shaft 64 and eccentric 65 rotate continuously imparting a reciprocating action to the pawl 67. This reciprocating action of the pawl 67 steps the spool 38 or 39 in engagement therewith, winding the ribbon so that it moves in the direction of tape 14 in operation of the device. When the frame 30 is freed for its 180 degree rotation by the release of stop member 57 or 58, pawl 67 will move forward slightly engaging stop 68. At the end 75 of a half revolution of the frame, the flange of the ribbon spool will engage the flared section of the pawl 67, camming it outward slightly and as the frame comes to rest the nose 69 of the pawl will engage the teeth of the ribbon spool winding the ribbon in the opposite direction on the spool but still feeding it in the direction of movement of tape 14.

It will be obvious to those skilled in the art that a hand mechanism for reversing the position of carriage 30 may be provided to turn the carrier 180 degrees for reversing the ribbon feed by eliminating bevel gears 5, 23, and 27, and the drum 4, and providing the usual spring drive motor arrangement, and by providing a hand button to turn gear 28. In such cases the operator charged with the duty of winding the spring mechanism can note the condition of the ribbon on the spools 38 and 39 when the main spring mechanism is hand wound and when the ribbon is almost unwound from the one spool and the other spool is almost filled the frame 130 is rotated 180 degrees by operating the hand button to reverse the ribbon feed.

It will be apparent to those skilled in the art that various other modifications of my invention may be made without departing from the spirit thereof. For example, instead of rotating the frame 30 in a horizontal plane the ribbon frame may be mounted for a 180 degree rotation about a horizontal axis.

Accordingly, having described only preferred embodiments of my invention, what is desired to be secured by Letters Patent and claimed as new is:

1. A telegraphic recorder comprising receiving means; marking means actuated by said receiving means; a record tape; means for advancing said record tape during the reception of signals; an ink ribbon having no normal tendency to move; and means for moving said ribbon in the direction of movement of said tape only during marking operations of said marking means.

2. A recorder for telegraphic signals; comprising a tape; an ink ribbon with a

- section thereof disposed adjacent said tape; marking means; means for bringing said marking means into engagement with said tape in response to received signalling impulses; and means for moving said tape and said ribbon in the same direction only while said marking means is in engagement with said tape to effect a record of the received signalling conditions on said tape.
3. A recording mechanism comprising a movable tape; marking means adapted to engage said tape for recording purposes; and an ink ribbon having no normal tendency to move disposed adjacent said tape movable in the direction of and with said tape only when said marking means is actuated to make a record on said tape.
4. In a signal recorder; a movable record tape; an inking ribbon; a reversible winding mechanism for said ribbon reversible during recording operations; marking means coacting with said tape and said ribbon to produce a record; and means for moving said ribbon in contact with and in the direction of movement of said record tape independently of the direction of winding of said ribbon on said ribbon mechanism.
5. The combination as set forth in claim 4 in which the movement of said record tape supplies the driving energy for the movement of said ribbon.
6. A tape recorder comprising a record member movable in a given direction during recording operations; an ink ribbon supplying the marking fluid for the making of said record; a reversible winding mechanism for said ribbon; said ribbon being movable in the direction of movement of said tape independently of the relative direction of winding of said ribbon on said winding mechanism.
7. A tape recorder in which the tape is movable to effect the marking thereon; an ink ribbon having no normal tendency to move for supplying marking fluid to said tape, of sufficient length to permit ink to seep to the ribbon sections utilized in the marking operation from the surrounding ribbon section before a reuse of any given section of the ribbon; and means for moving said ribbon adjacent said tape only in the direction of movement of said tape.
8. A movable tape recorder comprising marking means responsive to received signals for producing a record on said tape while in motion; and an inking mechanism comprising a discontinuous reversible ribbon movable only when marking signals are received and driven during all recording operations in the direction of movement of said record tape.
9. A telegraphic recording mechanism comprising a marker responsive to received signalling conditions; a movable tape upon which a record of the received signalling conditions are made; a ribbon; and an automatically reversible ink ribbon mechanism arranged to feed said ribbon continuously in the direction of movement of said record tape.
10. A tape recorder comprising a movable record tape; a marker responsive to received signalling combinations for recording the received signalling combinations on said tape; and an ink ribbon movable longitudinally only in the direction of movement of said strip during marking operations only; said ribbon being repeatedly reused in marking operation and of sufficient length to permit ink to seep to the used sections of the ribbon from the surrounding sections of the ribbon before reuse of any given section of the ribbon in a succeeding marking operation to permit continuous operation without loss of signals due to drying of the ribbon in the sections used for marking.
11. In a recorder; a marker; an ink ribbon mechanism coacting with said marker to produce a record; comprising a ribbon and a pair of reels on which said ribbon is wound; a platen member around which said ribbon passes disposed adjacent said marker; and means for interchanging the position of said reels to reverse the direction of winding of said ribbon thereon during receipt of marking signals without changing the direction of movement of said ribbon through the recorder.
12. The combination as set forth in claim 11 in which said last mentioned means is automatically controlled by the winding of said ribbon.
13. In a recorder; a marking means; a rotatable carriage; a platen member mounted on said carriage adjacent said marker; an inked ribbon mounted on said carriage passing round said platen member; a reversible winding mechanism mounted on said carriage; and means for rotating said carriage to reverse the direction of winding of said ribbon.
14. The combination as set forth in claim 13 in which said last mentioned means is automatically controlled by said ribbon.
15. The combination as set forth in claim 13 in which the axis of rotation of said carriage is in substantial alignment with the marking section of said marking means.
16. In a tape recorder; a spring motor; a tape driven from said spring motor in a single direction; a marker actuated in response to received signals; an inking ribbon having no normal tendency to move and of sufficient length to permit continuous marking operations adapted to coact with said marker to produce a record on said tape; and means driven by said spring motor for causing said ribbon to be driven in the direction of movement of said tape only when marking signals are received.

17. In a tape recorder; a spring motor; a tape driven by said spring motor; a marker responsive to received signaling combinations adapted to produce a record on said tape; a reversible carriage; an ink ribbon mounted on a winding mechanism on said carriage and fed adjacent to said tape and in the direction of movement of said tape; and means controlled by said ribbon for controlling the reversing operation of said carriage to reverse the direction of winding of said ribbon.

In testimony whereof I affix my signature.
ERNEST A. FALLER.
